CLOSURE FOR LIQUID CONTAINERS

Martin Klusch, Canton, Ohio

Application April 19, 1932. Serial No. 606,151

4 Claims. (Cl. 215—51)

My invention relates to closures or caps for liquid containers, and more particularly for the usual standard milk or cream bottles, and the caps being constructed and arranged for operation when placed on the bottles so that the bottles may be opened for pouring and again closed.

The usual milk bottle comprises a shell usually made of glass, and having a single opening or mouth formed therein, and through which the milk is introduced into or poured from the bottle.

The usual milk bottle mouth is formed with an enlarged internal tubular surface at its extremity which is connected by an annular ledge or seat with inner tubular surfaces of the bottle shell.

The usual closure for the mouth of the bottle comprises a cap of impregnated pulp or fiber board.

Such caps are inserted into the enlarged extremities of the mouths and seated upon the ledges of successive bottles from a stack of the caps by operation in most instances of a bottle capping machine.

Caps heretofore available and intended to be constructed and arranged so that the bottles supplied with the caps may be opened for pouring and again closed, have been unsatisfactory, for a number of reasons.

In some cases, such opening and closing caps have not permitted the proper flow of milk or liquid from the bottles when the parts of the caps have been placed in the open positions.

In other cases, such opening and closing caps have not been adapted for use in standard bottle capping machines, by reason of excessive thickness of the caps.

In most cases, the parts of such opening and closing caps have not been arranged for convenient and easy use on the bottles, particularly by children.

The objects of the present improvements are in general to overcome the foregoing disadvantages, and include, accordingly, the provision of a novel opening and closing cap for liquid containers such as milk bottles, the construction and arrangement of the cap being such that when the parts thereof are placed in the open position the liquid will flow freely from the container.

Further objects of the improvements include the provision of a novel opening and closing cap, stacks of which may be placed in a standard bottle capping machine for successively capping bottles by the usual operation of the machine.

Further objects of the improvements include the provision of a novel opening and closing cap

which is arranged for convenient and easy use on the bottle, and which is at the same time effective as a closure when the parts of the cap are placed in the closed position after the bottle has been opened one or more times by operation of the cap.

The foregoing and other objects are attained by the improvements, apparatus, parts, combinations, and sub-combinations, which comprise the present invention, and the nature of which is set forth in the following general statement, and preferred embodiments of which, together with their mode of use, are set forth in the following description, and which are particularly and distinctly pointed out and set forth in the appended claims forming part hereof.

The nature of the improved opening and closing cap or closure of the present invention may be described in general terms as including two interfitting members hinge connected with each other and preferably formed integrally from impregnated pulp or fiber board, and the two members when in their closed positions relative to each other comprising a circular closure disk of the same diameter and substantially the same thickness as the usual cap.

One of the members comprises a door member which is hinged at its inner straight end with the other member, which is a notched member.

The outer end face of the door member is arcuate as is also the outer peripheral face of the notched member, and the arcuate end face of the door member connects between the extremities of the arcuate peripheral face of the notched member to form an outer circular face for the cap as a whole, when the members are in the closed position.

The side faces of the door member preferably diverge from each other outwardly from the inner hinge end of the door member, and the door side faces are also preferably oppositely angled with respect to each other for interfitting with the preferably similarly angled side faces of the notch of the notched member, which notch side faces extend between the extremities of the arcuate outer face and the straight hinge base of the notch.

The hinge base of the notch, which as aforesaid is preferably integrally hinge connected with the inner straight end of the door member, is preferably located so that the depth of the notch with reference to the circumference of the circle of the outer face of the closed cap is substantially two-thirds of the diameter of the circle, whereby when the cap is in use on a con-

tainer, steady free pouring of the liquid from the container may be effected.

An improved opening and closing lever is provided for the door member and includes a handle tab located on the normally upper face of the door member, the handle tab including at one end one or more hooks which are engaged with the door member preferably at the hinge end thereof, and the tab and the outer end of the hooks extending from the hinge end of the door member towards the arcuate end thereof.

Preferred embodiments of the improved closure or cap, and the parts thereof, are illustrated in the accompanying drawing forming part hereof, in which the views are enlarged, and are as follows:

Figure 1 is a top plan view of the improved closure or cap, with the parts thereof in their relative positions for being applied to a bottle by operation of a usual bottle capping machine; Fig. 2, a bottom plan view thereof;

Fig. 3, a sectional view thereof as on line 3—3, Fig. 1;

Fig. 4, a side view thereof looking in the direction of the arrows 4—4, Fig. 1;

Fig. 5, a plan view illustrating the outline of a preferred blank made from preferably tinned sheet metal, from which the improved opening and closing lever is formed;

Fig. 6, a similar view thereof after a partial forming of the lever hooks to a position ready for the lever to be applied to the cap door member.

Fig. 7, an elevation view thereof looking in the direction of the arrows 7—7, Fig. 6; and

Fig. 8, a fragmentary vertical sectional view of top portions of a bottle in the mouth of which, one of the improved closures or caps has been inserted, and the cap parts being illustrated in full lines and in section as on line 8—8, Fig. 1, but with the opening and closing lever displaced from its position in Fig. 1 to its operating position relative to the door member and notched member of the cap, and the door member and lever member being illustrated in broken lines in their relative positions with each other and with the notched member after further movement of the lever member to open the door member.

Similar numerals refer to similar parts throughout the several views.

The illustrated embodiment of the improved opening and closing cap or closure is indicated generally by 10, and includes two members 11 and 12, preferably formed integrally from impregnated pulp or fiber board.

The member 11 comprises a door member having a straight inner end 13, an arcuate outer end face 14, and spaced side faces 15 and 16 connecting the inner end 13 and the outer end face 14.

The side faces 15 and 16 preferably diverge from each other longitudinally and outwardly from the inner end 13 to the outer end face 14. The side faces 15 and 16 are also oppositely angled with respect to each other transversely of the cap 10.

The other member 12 of the cap is preferably a notched member having an arcuate peripheral face 17, a notch base portion 18 which integrally connects with the hinge end 13 of the door member 11 along a straight hinging line or axis H which determines a boundary between the connected members 11 and 12, and about which the door member 11 is adapted to be swung for opening and closing the cap.

The notched member 12 furthermore includes side faces 19 and 20 extending from the base portion 18 to the ends of the peripheral face 17, the notch side faces 19 and 20 diverging and being angled respectively for interfitting with the side faces 15 and 16 of the door member 11, when the members 11 and 12 are in the closed position illustrated in full lines in the drawing.

When the members 11 and 12 are in the closed position, the arcuate end face 14 of the door member 11 connects between the extremities of the arcuate peripheral face 17 of the notched member 12, and forms an outer circular face for the cap 10 as a whole.

The base portion 18 of the notch is preferably located so that the depth of the notch with reference to the circumference of the circle of the outer face of the closed cap is substantially two-thirds of the diameter of the circle, whereby when the cap is in use on a container, and the door member is open, steady pouring of the liquid from the container may be effected.

The flat face 21 of the member 11 is the upper face in use, and the opposite flat face 22 is the lower face in use. The flat face 21' of the door member 11 is the upper face thereof, and becomes co-extensive with the flat face 21 of the notched member 12, and the flat face 22' of the door member 11 is the lower face thereof in use, and becomes co-extensive with the flat face 22 of the notched member 12, when the members are in the closed position.

The door member side faces 15 and 16, may be accordingly described as being oppositely angled with respect to the flat faces 21' and 22' of the door member; and similarly the notch side faces 19 and 20, interfitting in the closed position respectively with the door member side faces 15 and 16, may likewise be described as being angled with respect to the flat upper and lower faces 21 and 22 of the notched member.

An improved opening and closing lever indicated generally by 23 is located on the normally upper face of the door member, and the improved lever 23 includes a flat handle tab 24, preferably formed of tin plated relatively thin sheet metal. At one corner of one end of the tab 24, a hook 24—1 is formed, and at the other corner of the same end of the tab 24, a hook 24—2 is formed.

The hook 24—1 includes an apex or bend portion 25—1, and an outer end 26—1; similarly the hook 24—2 includes an apex or bend portion 25—2, and an outer end 26—2.

The apex or bend portions of the hooks are preferably located in apertures which may be formed by forcing the outer ends of the hooks through the integral cap, when the handle is in the semi-finished condition illustrated in Figs. 6 and 7, after which the outer ends 26—1 are bent over against the bottom face 22' of the door member 11, with the handle tab 24 lying against the upper face 21' of the door member 11.

The bend or apex portions of the lever 23 when in place on the cap 10, are preferably on the hinging line H, and the outer ends 26—1 and 26—2 of the hooks extend towards the outer end 14 of the door member, as does the outer end of the handle tab 24.

The lever 23 is also preferably formed with a laterally extending stop face 27 located intermediate the hook apex or bend portions and the opposite outer end of the tab.

When the cap 10 is ready for being applied to a bottle, the several parts of the cap are pref-

erably arranged in the positions illustrated in Figs. 1, 2, 3, and 4, with the handle tab 24 lying flat against the upper face 21' of the door member, whereby successive caps 10 of a stack of the 5 caps may be applied successively to bottles by operation of the usual bottling machine.

In Fig. 8 is illustrated the mouth end 28 of a milk bottle whose mouth is formed in the usual manner with an enlarged internal tubular surface 29 at its extremity, which is connected by an annular ledge or seat 30 with the inner tubular surface 31 of the bottle shell.

One of the improved caps 10 has been inserted upon the seat 30 of the mouth end 28 of the milk 15 bottle in Fig. 8, and the parts of the inserted cap are illustrated in full lines with the opening and closing lever 23 displaced from its position in Figs. 1, 2, 3, and 4, to its operating position relative to the door member 11 and the notch 20 member 12 of the cap.

The operating position of the lever 23 is attained by pulling upwards on the outer end thereof with the forefinger of the user, by which a partial opening of the hooks is effected, and the 25 lever slips downwardly through the hook apertures until the stop face 27 abuts against the upper face 21' of the door member.

Further movement of the handle lever 23 to the position illustrated in broken lines in Fig. 8 30 serves to open the door member, by lifting action of the hook outer ends 26—1 and 26—2.

The door member 11 may be opened and closed any usual number of times even when the door member and notch member are integrally formed 35 from pulp or fiber board, and after closing of the door member 11, by reason of the angle arrangement of the side faces 15 and 16 of the door member and the side faces 19 and 20 of the notch, a tight closing seal is effected.

40 For the purpose of attaining a tight closing seal when the cap members are in the closed position, it has been discovered that when the side faces of the door member make an angle of substantially 20° with a plane vertical with 45 respect to the flat normally upper face, and with the notch side faces similarly angled, the best results are attained.

I claim:

1. A closure for the mouth of a liquid container 50 and the like, including two members connected with each other along a straight hinging line determining a boundary between adjacent portions of the members, one of the members comprising a door member and being adapted for being swung about the hinging line, and an opening and closing lever having a hook at one end, the hook being connected with the door member adjacent the hinging line.

60

80

2. A closure for the mouth of a liquid container and the like, including two members connected with each other along a straight hinging line determining a boundary between adjacent portions of the members, one of the members comprising a door member and being adapted for being swung about the hinging line, and an opening and closing lever having a hook at one end, the hook being connected with the door member adjacent the hinging line, and the outer end of the hook extending away from the hinging line and towards the opposite outer end of the door member for exerting upward pressure on the door member to open the same when the lever is manipulated.

90

3. A closure for the mouth of a liquid container and the like, including two members, one of the members comprising a door member, the other member comprising a notched member and having an arcuate peripheral face and a notch base portion and notch side faces connecting the notch base portion with the extremities of the arcuate peripheral face, the door member having one end hinge connected with the notch base portion and an opposite arcuate outer end face and side faces connecting the hinge end and the arcuate end, and the side faces of the door member interfitting with the side faces of the notched member when the members are in closed position, the arcuate outer faces of the members when in the closed position determining a circle, and the length of the door member between its arcuate outer end face and the hinge end thereof being substantially two-thirds of the diameter of the circle determined by the members when in the 100 closed position.

105

4. A closure for the mouth of a liquid container and the like, including two members, one of the members comprising a door member, the other member comprising a notched member and having an outer peripheral face and a notch base portion and notch side faces connecting the notch base portion with the extremities of the outer peripheral face, the door member having one 110 end hinge connected with the notch base portion and an opposite outer end face and side faces connecting the hinge end and the outer end face and the side faces of the door member interfitting with the side faces of the notched member when the members are in closed position, the door member having a flat normally upper face, and the side faces of the door member being oppositely angled with respect to each other each at substantially 20° with a plane vertical with 115 respect to the flat face, and the similar side faces 120 of the notched member being similarly angled.
